TYPEWRITING MACHINE

Henry Allen Avery, Groton, N. Y., assignor to
 L. C. Smith & Corona Typewriters Inc., New
 York, N. Y., a corporation of New York

Application January 15, 1932, Serial No. 586,725

4 Claims. (Cl. 197—127)

This invention relates to improvements in typewriting machines and more particularly to improvements in paper feeding and guiding means for said machines.

The invention provides a highly efficient paper feeding and guiding means the parts of which are of light weight, very compactly arranged and of exceptionally small number, thus affording a paper feeding and guiding means especially suitable for small portable typewriting machines.

The invention also provides a paper feeding and guiding means wherein a paper guiding table and a plurality of feed rolls are yieldably urged toward the platen and are shifted from the platen to release the paper by an exceedingly simple means correlated therewith to act thereon in a manner insuring highly efficient paper feeding and paper releasing actions.

Other objects and advantages of the invention will appear from the following description of the preferred embodiment of the invention illustrated in the accompanying drawing.

In the drawing,

Fig. 1 is a top plan view of the platen carriage of a typewriting machine provided with the improved paper feeding and guiding mechanism;

Fig. 2 is a vertical sectional view on the line 2—2 of Fig. 1, showing the feed rolls engaged with the platen;

Fig. 3 is a vertical sectional view on the line 3—3 showing the feed rolls and paper table released;

Fig. 4 is a fragmentary bottom plan view showing parts of the platen carriage and paper table; and

Fig. 5 is a fragmentary perspective view of the paper feeding and guiding means inverted to clearly show certain features of construction thereof.

The parts of the improved paper feeding and guiding means are shown mounted on the platen carriage of a portable typewriting machine, the platen roller 10 having its shaft 11 journaled in bearings 12 on the end plates 13 of the platen carriage, which end plates are connected by the base plate 14 of the carriage. The platen roll is rotatable by the usual finger wheels 15 on the platen shaft, or by the usual line spacing mechanism which includes a ratchet wheel 16 held to one end of the platen roll.

A sheet metal paper supporting and guiding table 17 extends under the platen roll between the carriage and plates and between the platen roll and the carriage base plate, said table being curved or bowed transversely of the platen with

its concave face uppermost or nearest the platen. In the front edge of table 17 there is a long shallow recess or notch 18, the ends of which are located equidistant from the table ends, and the rear longitudinal edge of which is preferably formed with a short pendent lip or flange 19. A long front feed roller 20 fixed on a front feed roll shaft 21 is located in this recess 18, the ends of shaft 21 being journaled in bearings closely adjacent the convex face of table 17, and each formed by the slightly pendent hook-like forward end 22 of a lug 23 formed on the paper table. Roller 20 projects through the recess 18 beyond the opposite or concave face of the table. There is one lug 23 extending forward from the rear edge of recess 18 at each end of the recess, the ends of shaft 21 and the ends of roller 20 being equidistant from the respective ends of the table, so that the front roll is centered longitudinally of the table which, in turn, is similarly centered relatively to the platen longitudinally of the platen as hereinafter described. The open throats of the hook bearings 22 face toward the paper table.

A rear feed roll shaft 24 longer than shaft 21 extends longitudinally of the table 17 at the convex or under face of the table and has its ends journaled in the slightly pendent hook-like ends 25 of two bearing lugs 26 formed on the table at the outer ends of the forward edges of two relatively short longitudinal slots 27 in the table. The open throats of hook bearings 25 face toward the convex face of the table. Two short rear feed rollers 28 are fixed on shaft 24 and project through the short slots 27 beyond the opposite or concave face of the table a substantial distance to the rear of the front feed roller. Slots 27 and rollers 28 are equal distances from the respective ends of the paper table, shaft 24 and its bearings being centered longitudinally of the table with the rollers 28 equidistant from the shaft ends and each crossing the vertical fore and aft or transverse plane of a different end of the longitudinally centered front feed roller 20. This staggered arrangement of three feed rolls (a forward and two rear rolls) is effective to feed the paper smoothly and in a straight path.

The table is normally supported or held up to yieldably hold the feed rollers against the platen roller, or against paper fed between the platen roller and said rollers, at one point only, as hereinafter described, the table supporting means loosely engaging or merely abutting the table at the convex face of the table. The table,

thus loosely supported at one point only, is maintained in longitudinally centered relation with the platen roller, i. e. with its ends equidistant from the ends of the platen roller, by a pair of 5 positioning pins or studs 29 depending from the table and of sufficient length and diameter to always extend loosely (with a small radial clearance) through a pair of holes 30 in the base plate 14 of the platen carriage. Pins 29 are aligned 10 longitudinally of the table in a line passing approximately midway between the feed roll shafts, said pins being located equal distances from and close to the respective ends of the table and also being freely tilttable in all directions 15 in the holes 30.

The means for normally vertically supporting the table with the table and rollers yieldably pressed toward the platen roller to feed paper through the machine comprises a rock shaft 31 20 extending longitudinally of the carriage and platen roller at the rear of the carriage, paper table, and platen roller. Shaft 31 has a reduced inner end 34 journalled in a bracket 32 held to the carriage base plate to the left of the middle of the carriage, and said shaft extends to the right hand end plate of the carriage where its outer end is journalled on the inner end of a pivot screw 33 tapped through said plate. A forwardly extending rock arm 35 fixed on shaft 31 is located in 30 the medial fore and aft vertical plane of the platen roller and paper table and is bent to clear the table in all vertically shifted positions of the table except at its forward end or tip which is adapted to loosely abut or contact the under or convex face of the table at a point in said medial plane midway between the front and rear feed rolls or equidistant from said shafts and the axes of the front and rear feed rollers.

At its outer or right hand end, at the inner face 40 of the right hand end plate of the carriage, the rock shaft 31 has fixed thereon a rock arm 36 extending forwardly between the platen shaft 11 and base plate 14 of the platen carriage and normally held yieldably drawn or rocked upward by a coil spring 37 to thereby hold arm 35 rocked upward in a position in which it holds the table 17 lifted a substantial distance from the base plate 14 to press the feed rolls against the platen roller, or against paper interposed between the platen 50 roller on the one hand and the feed rollers and paper table on the other hand, this position of the parts being shown in Figs. 1, 2 and 5. Spring 37 is connected at its lower end to the forward end of rock arm 36 and extends upward in front of the platen shaft to an anchor stud or pin 38 projecting inward from the right hand end plate of the carriage.

It will be observed that the system of feed rollers engages the platen roller equally at both sides 60 of a medial transverse plane A—A of the platen and that the front and rear feed roller axes are equal distances from a line parallel with said axes or a plane B—B through the platen axis intersecting plane A—A at the contact end of arm 35, so that the paper table is normally supported 65 against downward or feed roll releasing movement at a single point located centrally of the feed roller system and midway the ends of the platen roller and paper table, at the intersection of planes A—A and B—B, by the front end edge of arm 35 which urges the feed rollers equally to the platen roller by pressure transmitted to the table at said point from the single spring 37. This method of table and feed roller support together with the loose fit of the positioning pins 70

29 in holes 30 permits a limited universal tilting of the table to compensate for slight inequalities in the platen and feed rollers and the paper and insures straight feeding of the paper at an even rate.

The table and feed rollers may be lowered to the paper-releasing or feed-roll cast-off position shown in Fig. 3 by rocking shaft 31 against the pull of spring 37. For this purpose, and to lock the parts in cast-off position, a hand-operated 80 release lever 39 of bellcrank form is pivoted at the inner face of the right hand end plate 13 of the carriage on a pivot 40 mounted on said plate for fore and aft swinging of the upstanding handle arm of the release lever. The other arm of 90 the bellcrank hand lever carries at its end a laterally projecting pin or stud 41 which works in a recess 42 in the upper edge of rock arm 36, and normally engages the rearwardly facing front end wall of said recess and is slightly out of contact 95 with the bottom or upwardly facing wall of said recess when the feed rolls contact the platen, as shown in Fig. 2. The recess is of such length and depth that when the handle arm of lever 39 is drawn forward to swing the normally forwardly 100 extending stud-carrying arm downward, arm 36 is depressed to depress arm 35 sufficiently to allow the table 17 to seat on the carriage base plate 14 (affording maximum feed roll clearance from the platen in cast-off position), and stud 41 engages 105 the forwardly facing rear end wall of the recess 42 with the engaged lever and arm parts in dead center relation to lock the parts in paper-releasing or feed-roll cast-off position, as shown in Fig. 3.

A suitable letter space scale 43 is held by screws 110 44 to pendent lugs 45 at the front edge of paper table 17.

What I claim is:

1. Paper feeding means comprising a platen carriage having a base plate provided with apertures aligned longitudinally of the carriage, a roller platen journalled on the carriage to extend longitudinally of the carriage, a paper table interposed between the platen and base plate and shiftable facewise between said platen and base 115 plate, pins fixed at one end to said table in alignment longitudinally of the table and loosely fitting and telescoping in the base plate apertures during facewise shifting of the paper table, a system of tandem feed rolls journalled on the 120 paper table to shift as a unit with the table toward and from the platen, a single spring-urged device normally yieldingly supporting the table out of contact with the base plate to press the system of feed rolls to the platen, said device 125 being engageable with the table solely at a point on the table located centrally of the system of feed rolls, and manually shiftable means on the carriage for actuating said spring-urged means to lower the table to the base plate of the carriage.

2. Paper feeding means comprising a platen carriage having a base plate provided with apertures aligned longitudinally of the carriage, a roller platen journalled on the carriage to extend 140 longitudinally of the carriage, a paper table interposed between the platen and base plate and shiftable facewise between said platen and base plate, pins fixed at one end to said table in alignment longitudinally of the table and loosely fitting and telescoping in the base plate apertures 145 during facewise shifting of the paper table, a system of tandem feed rolls journalled on the paper table to shift as a unit with the table toward and from the platen, a single spring- 150

urged arm pivoted on the carriage to swing toward and from the platen and extending transversely of the platen under the table, said arm being normally loosely engaged under the paper table 5 midway the ends of the table to yieldingly hold the table spaced above the base plate and urge the system of feed rolls to the platen and being the sole means for holding the table spaced above the base plate of the carriage, and manually shift- 10 able means on the carriage for swinging said arm downward at will.

3. Paper feeding means comprising a roller platen, a platen support in which the platen is journaled having a base plate which extends longitudinally of the platen below the platen and is provided with apertures aligned longitudinally of the platen, a paper table interposed between the platen and base plate, pins pendent from the table and having loose sliding fits in the base 15 plate apertures for guiding the table to shift facewise between the platen and base plate, a system of tandem feed rolls journaled on the table to shift as a unit with the table, a rock shaft journaled on the support and extending longitudinally of the platen, a single table supporting rock arm extending forward from said 20 shaft under the table and engageable with the table solely at a point on the under face of the table located centrally of the system of feed 25 rolls, a second rock arm extending forward from said shaft adjacent one end of the support, a 30

spring connected to said second arm and normally urging the same upwardly to cause the first arm to yieldingly hold the table out of contact with the base plate for pressing the feed rolls to the platen, and a manually shiftable cam device piv- 80 otted on the support and shiftable about its pivot to depress and lock down the second arm.

4. Paper feeding means comprising a roller platen, a platen support in which the platen is journaled, said support having a base plate under the platen provided with apertures aligned longitudinally of the platen, a paper table between the platen and base plate having pendent pins 85 slidably engaged in said apertures, a system of tandem feed rolls journaled on the table and engageable with the platen, a rock shaft journaled on the support and extending longitudinally of the platen and having a single table supporting arm, a spring normally rotatively urging said rock shaft in a direction to cause said arm to hold the table elevated above the base plate with the feed rolls pressed to the platen, said arm engaging under the table at a point located centrally of the system of feed rolls to hold the table elevated above the base plate, and manually operable means adjacent one end of the support for rocking said shaft in opposition to said spring to lower the table for casting off the feed rolls from the platen.
